FRAME FOR A CHARCOAL GRILL

Maxon E. Gilbert, North Scituate, R. I.

Application April 6, 1953, Serial No. 24,366

Term of patent 14 years

(Cl. D81—10)

To all whom it may concern:

Be it known that I, Maxon E. Gilbert, a citizen of the United States of America, residing in North Scituate, county of Providence, State of Rhode Island, have invented a new, original, and ornamental Design for a Frame for a Charcoal Grill, of which the following is a specification, reference being had to the accompanying drawing, forming a part thereof.

Fig. 1 is a front elevational view of a frame for a charcoal grill showing my new design; and

Fig. 2 is a side elevational view thereof.

The table top portions of the frame are substantially plain.

I claim:

The ornamental design for a frame for a charcoal grill, substantially as shown and described.
